UNITED STATES PATENT OFFICE.

MOSES M. MARCUSE, OF NEW YORK, N. Y., ASSIGNOR TO WEST DISINFECTING COMPANY, OF NEW YORK, N. Y., A CORPORATION OF NEW YORK.

CONTAINER FOR TOILET REQUISITES.

1,179,020.

Specification of Letters Patent. Patented Apr. 11, 1916.

Application filed June 5, 1914. Serial No. 843,175.

To all whom it may concern:

Be it known that I, MOSES M. MARCUSE, a citizen of the United States, and resident of the borough of Manhattan, in the city and 5 State of New York, have invented a new and useful Improvement in Containers for Toilet Requisites, of which the following is a specification.

My invention relates to a container for 10 toilet requisites, which is particularly well adapted for delivering interfolded sheets of paper, as, for instance, paper towels, arranged in a stack within the receptacle.

The object of this invention is to provide 15 certain improvements in the construction, form and arrangement of the several parts of the receptacle whereby the sheets may be readily withdrawn one by one without undue friction.

20 A practical embodiment of this invention is represented in the accompanying drawings, in which,

Figure 1 represents a plan view of the receptacle, Fig. 2 represents a front elevation of the same, Fig. 3 represents a transverse section taken in the plane of the line A—A of Fig. 2.

The front wall of the receptacle is denoted by 1; its bottom, formed by inclined 25 or receding upper and lower members, by 30 2, 3; its ends by 4, 5; its back by 6; and its top by 7. The front wall 1 is hinged at 8 and its free end is provided with a suitable lock 9 controlled by a key 10. The bolt 11

35 of the lock is arranged to engage an inwardly turned peripheral flange 12 which extends around the front of the receptacle.

This flange 12 serves to materially strengthen the receptacle at this point. A sheet 40 delivery slot 13 extends horizontally across the inclined bottom of the receptacle and it is formed between the adjacent edges of the upper and lower bottom members 2 and 3.

To facilitate the removal of the interfolded sheets and to reduce the friction thereon, the adjacent edges of these upper and lower bottom members are curved outwardly as 45 shown at 14, 15, to form convexed walls for the slot 13. A yielding false bottom or take

50 up device is located in close proximity to the slot 13 and comprises, in the present instance, a plate 16, hinged to the back at 17. This plate is interposed between the interfolded sheets and the lower member 3, and 55 springs 18 are located between the plate 16

and the lower member 3, thereby serving to hold the plate 16 normally away from the lower member 3. The free end of the plate 16 is curved outwardly as shown at 16*, so as to conform with the convexed wall 15 60 of the slot 13.

A follower 19, hinged at 20 to the front wall 1, is provided with fingers 21, which are arranged to automatically exert pressure upon the interfolded stack of sheets 65 when it has decreased to approximately a predetermined point. A series of abutments 22 are arranged upon the front wall 1, and the follower 19, so as to prevent the edges 70 of the stack from flipping up and becoming displaced as the sheets are drawn from the bottom.

To utilize the space within the receptacle 75 at the top, a partition 23 is secured to the receptacle, which partition forms the bottom of a container for such articles as a comb and brush, etc., (not shown). The top 7 is hinged at 24 to the back and provided with a suitable lock 25 controlled by a key 26. The bolt 27 of the lock is adapted 80 to engage a peripheral flange 28, which extends around the top of the receptacle.

The hinged front wall 1 of the receptacle 85 may be provided with a suitable window 29 by means of which it may be ascertained when the supply of sheets within the receptacle is nearly exhausted. A mirror 30 may also be secured to the front wall to complete the toilet requisite.

The container may be secured to a wall 90 or support by means of straps 31, 32, 33, fixed to the back 6.

The yielding false bottom 16 is arranged 95 within the container to reduce the friction caused by the sheet in position to be delivered carrying the leading edge of the next succeeding interfolded sheet upwardly with it so as to present its leading edge through the slot 13 for the next delivery. This upward movement of the leading edge of each sheet would cause it to crowd until it became crimped and wrinkled were it not for the yielding of the false bottom which gives ample room for the pulled sheet and the sheet to be turned. The false bottom 105 returns to its normal position as soon as the pulled sheet is removed from the container.

The front wall 1 is permitted to swing 110 to the position shown in dotted lines in Fig. 3, in which position, the container may be

readily replenished with the interfolded sheets. It will also be seen that the follower 19 being hinged to the front wall 1, is also withdrawn from the container by the 5 wall, thereby leaving the container free from obstruction.

It is evident that various changes might be resorted to in the construction, form and arrangement of the several parts without 10 departing from the spirit and scope of my invention, and hence I do not wish to limit myself strictly to the structure herein shown and described, but

What I claim is:—

- 15 1. A container for a stack of interfolded sheets having an inclined bottom with a delivery slot therethrough and a yielding false bottom within the container at the bottom thereof.
- 20 2. A container for a stack of interfolded

sheets having a delivery slot in its bottom, a front door for the container and a follower hinged to the door and arranged to engage the top of the stack when the stack has been decreased to substantially a predetermined 25 point.

3. A container for a stack of interfolded sheets having an inclined bottom with a delivery slot therethrough and a spring-pressed yielding false bottom hinged at the 30 back of the container and having its free end in proximity to the delivery slot.

In testimony, that I claim the foregoing as my invention, I have signed my name in presence of two witnesses, this 22nd day of 35 May, 1914.

MOSES M. MARCUSE.
